US00D877339S

(12) **United States Design Patent** (10) **Patent No.:** **US D877,339 S**
(45) **Date of Patent:** **** Mar. 3, 2020**

(54) **PULSE OXIMETRY**

(71) Applicant: **Shenzhen Jumper Medical Equipment Co., Ltd.**, Shenzhen, Guangdong (CN)

(72) Inventors: **Zhiping Xian**, Shenzhen (CN); **Yongjie Gao**, Shenzhen (CN); **Hui Yi**, Shenzhen (CN)

(73) Assignee: **Shenzhen Jumper Medical Equipment Co., Ltd.**, Guangdong, Shenzhen (CN)

(**) Term: **15 Years**

(21) Appl. No.: **29/667,068**

(22) Filed: **Oct. 18, 2018**

(30) **Foreign Application Priority Data**

May 30, 2018 (CN) 2018 3 0263732

(57) **CLAIM**

The ornamental design for a pulse oximetry, as shown and described.

DESCRIPTION

FIG. 1 is a front elevational view of a pulse oximetry showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof; and,

FIG. 7 is front, top, and left perspective view thereof.

The broken lines show portions of the pulse oximetry that form no part of the claimed design.
